[57] CLAIM

The ornamental design for an auxiliary music stand for a piano, as shown and described.

DESCRIPTION

FIG. 1 is a front elevational view of an auxiliary music stand for a piano showing my new design;

FIG. 2 is a right side elevational view thereof;

FIG. 3 is a rear elevational view thereof;

FIG. 4 is a top plan view thereof;

FIG. 5 is a bottom plan view thereof;

FIG. 6 is a front perspective view thereof;

FIG. 7 is a rear perspective view thereof; and,

FIG. 8 is a perspective view of the auxiliary music stand of my design with a piano being shown therein in dotted lines to illustrate the environment of use.

FIG. 2
